UNITED STATES PATENT OFFICE

ANDREW WEIMAR, OF PHILADELPHIA, PENNSYLVANIA, ASSIGNOR TO WEIMAR BROTHERS, OF PHILADELPHIA, PENNSYLVANIA, A FIRM CONSISTING OF ANDREW WEIMAR AND WILLIAM D. WEIMAR

TAPE LOOM

Application filed May 3, 1930. Serial No. 449,528.

This invention relates to means for converting an ordinary single deck fly-shuttle narrow-ware or tape loom, which usually has from forty to sixty strips of tape undergoing manufacture at one time, into what may be termed a partial double-deck loom.

Single deck looms are well known and complete double deck looms are well known. Double deck looms, however, have not been successful for various reasons including the difficulty encountered in getting skilled operators to operate them. Another disadvantage of full double deck looms resides in the added weight of the double deck which requires that the speed of such looms be greatly reduced from that of a single deck loom, for example, to 150 beat-ups a minute, whereas single deck looms are ordinarily operated at about 200 beat-ups a minute.

I have found that by applying auxiliary decks at spaced intervals along the lay of an ordinary single deck loom the normal speed of 200 beat-ups per minute may be maintained and that no difficulty is experienced in obtaining skilled operators to work such machines, for the reason that instead of having to reach over the top of the upper deck in tying up broken warp ends, etc., as in the full double deck loom the operators can readily reach around the sides of the auxiliary decks for the same purposes.

Other advantages of operation and construction will be fully disclosed hereinafter, reference being had to the accompanying drawings, of which:

Figs. 1 and 1a constitute a face view of the lay of a loom made in accordance with the principles of my invention;

Fig. 2 is an enlarged face view of a portion of the lay;

Fig. 3 is a transverse section taken on the line 3—3, Fig. 1a;

Fig. 4 is a transverse section taken on the line 4—4, Fig. 1a;

Fig. 5 is a perspective view of an element of the single deck portion of the lay;

Fig. 6 is a perspective view of an element of the double deck portion of the lay;

Fig. 7 is a perspective view of one of the reed units;

Figs. 8 and 9 are perspective views of one of the shuttle operating fingers; and

Fig. 10 is a detail section taken on the line 10, 10, Fig. 2.

In the accompanying drawings, the lay beam of an ordinary single-deck loom is illustrated at 1, 2, 2 indicate the usual form of shuttle guide brackets which are secured to the lay beam 1 by screws 3, 3. In an ordinary sixty strip single-deck loom there would be sixty-one of these brackets 2 and between each adjacent pair of brackets 2 is normally located a reed comb 4, through which the warp ends of the strips of tape extend.

Secured to each of the brackets 2 by means of screws 5, 5 and 6, 6 are guide blocks 7 and 8 respectively. Each pair of guide blocks 7 and 8 constitute a raceway 9 for a shuttle 10 which carries the weft thread back and forth across the reed comb 4 in the open shed formed by the warp threads extending therethrough.

In its travel, the shuttle 10 is passed from the raceway 9 of one bracket 2 to the raceway 9 of the next adjacent bracket 2, the shuttle 10 being engaged by a finger 11, such as shown in Fig. 8, which is secured to and projects vertically from an operating bar 12 longitudinally slidably mounted in a groove 13 formed in the lay beam 1.

The actuating bar 12 receives longitudinal reciprocatory movement, whereby the fingers 11 are moved from the position shown in Fig. 2 of the drawing at the right hand end of each guideway 9 to the left hand end of the said guideway which throws the shuttle 10 from the guideway 9 of one bracket 2 into the guideway 9 of the next bracket across the intervening space between the ends of the relatively spaced guideways 9, 9 and in front of the reed comb 4. Reverse movement of the bar 12 moves the shuttles 10 in the corresponding reverse direction.

The present invention consists primarily in substituting for some of the usual guide supporting brackets 2 at predetermined places along the lay of the loom, auxiliary brackets, such as indicated at 20, 20, and as shown in Fig. 6; each bracket 20 having a lower tongue portion 21 corresponding to

the lower tongue portion 22 of the ordinary brackets 2. The tongue 21 of the brackets 20 are drilled in the same manner as the tongue portions 22 of the ordinary brackets 2, 5 so as to be interchangeable therewith, and adapted to receive the ordinary securing screws 3 in the same general manner as the brackets 2.

The body portions of the brackets 20 are 10 adapted to receive the lower deck guide blocks 7 and 8 in the same general manner as the brackets 2 and in addition thereto the brackets 20 are provided with upwardly extending arms 23, 23, between which, in each bracket 15 20, is provided an upper reed comb 4a.

Secured to the right side arm 23 of one bracket 20 and to the left side arm of the next adjacent bracket 20 are guide blocks 7a and 8a between which are formed the upper 20 raceways 9a for the upper shuttles 10a.

Certain of the shuttle-operating fingers 11 are replaced by fingers 111 which are adapted to receive, support and operate an upper finger-operating bar 12a on which is provided shuttle-operating fingers 11a for operating the upper-deck shuttles 10a.

The principal object of this invention is to arrange the auxiliary decks at spaced intervals along the loom. Each auxiliary deck 30 to accommodate about four shuttles, providing sufficient space, equal to about four shuttles or more, between the auxiliary upper-decks so that the operators may readily reach in between the auxiliary decks to make necessary repairs or adjustments at the back of the lay.

Should it be necessary or desirable at any time to change the loom back to a single-deck machine for some classes of work, the brackets 20 may, by virtue of their interchangeability with the lower brackets 2, be readily removed and the usual low brackets 2 reinserted in place thereof, which is impossible with the ordinary double-deck loom.

45 The shuttle-operating fingers 111 are likewise made in a manner capable of interchangeability with the fingers 11 in the operating bar 12 so that an upper operating bar 12a of any desired length may be applied 50 at any point desired, to accommodate any desired number of upper shuttle-operating fingers 11a.

Herein lies another feature of the present 55 invention, i. e. all the shuttles of both the regular lower-deck and those of the upper auxiliary decks are actuated from and by the one single actuating bar 12 which in turn is actuated by a single operating mechanism 60 located at one end of the lay 1. This operating mechanism is of the usual construction, comprising a vertical slotted bracket 31 in which operates a block 32.

In the block 32 is rotatably mounted a crank pin 33 which is secured to a crank arm 65 34. The crank arm 34 is secured to the end

of a shaft 35 which is rotatably mounted in a bearing 36 carried by the lay 1. The shaft 35 is provided with a pulley or sprocket wheel 37 around which passes a belt or drive chain 38. The operating element 38 is connected to a suitable rocking mechanism (not shown) which effects rocking of the shaft 35 and a consequent reciprocation of the shuttle-actuating bar 12.

In order to prevent excessive wear of the bar 12 and the walls of the slot 13 in which it is slidably mounted, as could be caused by the tendency of the bar 12 to fall forwardly by the oscillation of the lay 1, I provide fixed brackets 40 on the lay 1, and each bracket comprises a rail 41 against which a roller 42 operates, each roller or shoe 42 being carried by a standard 43 which is rigidly secured to the shuttle-actuating bar 12.

As shown in Figs. 8 and 9, the fingers 11 and 111 respectively are provided with rectangular shanks 45 which snugly fit the same correspondingly shaped apertures 46 in the shuttle-actuating bar 12. If desired, these shanks and receiving apertures may be of a tapering nature to more securely cause the shanks to tightly fit the openings.

The reed combs 4, as above noted, ordinarily occupy positions between each adjacent pair of low brackets 2, each comb being provided with a lower head 50 and an upper head 51.

The lower head 50 fits in a groove 52 formed in the back upper edge of the lay 1, the ends 53, 53 of the head 50 abutting pads 54, 54 formed on the sides of the brackets 2, to keep the combs in proper position longitudinally of the lay 1. The heads 50 are held in the groove 52 by a longitudinally extending bar 55 secured to the back of the lay 1 by screws 56.

The upper heads 51 of the lower-deck reed combs 4 ordinarily are disposed between parallel bars 60 and 61, see Fig. 10, secured to the front and back faces of the brackets 2, by screws 62, and extending longitudinally of the lay 1, the ends 63 of the upper heads 51 abutting pads 64 formed on the opposite sides of said brackets 2.

Each bracket 20 intermediate its side edges 24, 24 is of equal width to the corresponding measurement of each bracket 2 intermediate the outer surfaces of the oppositely disposed pads 54, 54 and 64, 64 respectively, so that when any of the brackets 2 are replaced by brackets 20 the reed comb cavities 25 between brackets will be alike.

When such replacement takes place the reed comb retaining bars 60 and 61 are cut in the manner shown in Fig. 2, the front bars 61 stopping at the inner edge 24a of the outermost arm 23 of the inserted bracket 20 and the end of the bar being secured to the arm of the bracket by a screw 6b which is threaded into the opening in the arm which has been pro-

vided for the screws 6a which secured the lower elements 8a of the upper shuttle guide 9a to the brackets 20, it being noted that the said elements 8a, 8a are in alignment with the 5 retaining bars 60, 61, longitudinally of the lay 1 of the loom. The back bar 60 stops adjacent the outermost edge 24 of the bracket 20.

The upper heads 51 of the lower reed combs 4 which are disposed between adjacently positioned high brackets 20 are held in their cavities 25 against longitudinal movement relative to the lay 1 between opposed side edges 24, 24 of the brackets 20 and against lateral movement relative to the lay at their backs by lugs 70, 70, which project in opposite directions from the opposite side edges 24, 24 of each bracket 20.

Each bracket 20 is provided with a cavity 25a for the reception of the upper reed combs 20 4a of the auxiliary decks. Each cavity 25a is formed between the inner opposed edges 24a, 24a of the arms 23, 23 of the bracket 20. Extending across the bracket at the back thereof is a rib 75 between which and the back 25 face of the upper element 7 of the lower shuttle guideway 9, the lower head 50a of the upper reed comb 4a rests. A bottom rib 76, which also extends between the arms 23, 23, holds the reed comb 4a against downward 30 vertical movement, see Fig. 4.

The upper head 51 of the upper reed comb 4a is held against lateral movement, relative to the lay 1, between a rib 70a, extending between the arms 23, 23, and a front bar 71 secured to the front faces of the arms 23, 23 by screws 72.

In order to give the machine when equipped with the auxiliary decks a ship-shape appearance and to provide a maximum amount 40 of space between auxiliary decks I remove the upper portions of the outermost arms 23 at the extreme ends of each auxiliary deck, as indicated at 23a, 23a in Fig. 2, as there is no use for these particular portions at that time.

45 From the above, it will be obvious that by merely providing a set of special shuttle guide supporting brackets which are interchangeable with the ordinary low shuttle guide supporting brackets of an ordinary single-deck 50 tape loom, and by providing a set of special interchangeable shuttle operating fingers, I can readily convert an ordinary single-deck loom into a partial or full double-deck loom, but for the reasons noted in the preamble of 55 this specification I prefer to provide merely auxiliary decks at spaced intervals along the lay of the loom.

I claim:

1. In a narrow-ware loom, a lay comprising a lower shuttle deck extending substantially the full length thereof, a plurality of relatively short auxiliary decks disposed respectively at spaced intervals along the lay of the loom above the said lower deck, a series 65 of shuttles operable in each deck, an operating

finger for each shuttle, a lower bar carrying the operating fingers of the lower deck, a plurality of auxiliary bars carrying the operating fingers of the auxiliary decks, respectively, and supported from the said lower bar by 70 certain of the said lower fingers thereon, and a single actuating mechanism for all of said fingers, cooperating solely with the said lower bar.

2. In a narrow-ware loom, a lay comprising a lower shuttle deck extending substantially the full length thereof, a plurality of relatively short auxiliary decks disposed respectively at spaced intervals along the lay of the loom above the said lower deck, a series 80 of shuttles operating on each deck, an actuating bar for the shuttles of the lower deck, an actuating bar for the shuttles of each of said auxiliary decks, means for supporting the auxiliary deck bars on the lower deck bar, 85 and means for actuating the lower deck bar to operate all of said bars as a unit.

3. In a narrow-ware loom, a lay comprising a lower shuttle deck extending substantially the full length thereof, a plurality of relatively short auxiliary decks disposed respectively at spaced intervals along the lay of the loom above the said lower deck, a series of shuttles operating on each deck, an actuating bar for the shuttles of the lower deck, an actuating bar for the shuttles of each of said auxiliary decks, means for supporting the auxiliary deck bars on the lower deck bar, means for actuating the lower deck bar to operate all of said bars as a unit, and means 90 for guiding the bars to prevent lateral movement thereof.

4. In a narrow-ware loom, a lay comprising a lower shuttle deck extending substantially the full length thereof, a plurality of relatively short auxiliary decks disposed respectively at spaced intervals along the lay of the loom above the said lower deck, a series 105 of shuttles operating on each deck, an actuating bar for the shuttles of the lower deck, an actuating bar for the shuttles of each of said auxiliary decks, means for supporting the auxiliary deck bars on the lower deck bar, means for actuating the lower deck bar to operate all of said bars as a unit, means for 110 guiding the bars to prevent lateral movement thereof comprising a rail carried by and disposed at some distance above the lay, and a shoe carried by one of the bars and riding against said rail.

5. In a narrow-ware loom, a lay having a lower shuttle deck comprising a series of low brackets respectively supporting a series of shuttle-guiding elements, and an auxiliary deck disposed above the lower deck and comprising a series of tall brackets interchangeable with the said low brackets, said tall brackets supporting a lower series of shuttle-guiding elements in alignment with those carried by the said low brackets to complete the 125 130

said lower deck, and an upper series of shuttle-guiding elements disposed above the said lower series and constituting the said auxiliary deck.

- 5 6. In a narrow-ware loom, a lay having a lower shuttle deck comprising a series of low brackets respectively supporting a series of shuttle-guiding elements, an auxiliary deck disposed above the lower deck and comprising a series of tall brackets interchangeable with the said low brackets, said tall brackets supporting a lower series of shuttle-guiding elements in alignment with those carried by the said low brackets to complete 10 the said lower deck, and an upper series of shuttle-guiding elements disposed above the said lower series and constituting the said auxiliary deck, a reed comb between each adjacent pair of said brackets on said lower 15 deck, and a reed comb carried by each of said tall brackets on said auxiliary deck.

7. In a narrow-ware loom, a lay having a lower shuttle deck comprising a series of low brackets respectively supporting a series of shuttle-guiding elements, an auxiliary deck disposed above the lower deck and comprising a series of tall brackets interchangeable with the said low brackets, said tall brackets supporting a lower series of shuttle-guiding elements in alignment with those carried by the said low brackets to complete 20 the said lower deck, and an upper series of shuttle-guiding elements disposed above the said lower series and constituting the said auxiliary deck, a reed comb between each adjacent pair of said brackets on said lower deck, and a reed comb carried by each of said tall brackets on said auxiliary deck, the lower ends of the reed combs of the lower 25 deck being mounted in a groove formed in said lay and held therein by a bar secured to the lay and extending longitudinally thereof, and the upper ends of those of said reed combs disposed between said low brackets being held between front and rear parallel bars secured to said low brackets, lugs on 30 said tall brackets in alignment with the rear-most of said parallel bars, and the lower shuttle guide elements of the auxiliary deck disposed in alignment with the frontmost of said parallel bars for supporting the upper ends of the reed combs of the lower deck disposed between said tall brackets.

9. In a narrow-ware loom, a lay having a lower shuttle deck comprising a series of low brackets respectively supporting a series of shuttle-guiding elements, an auxiliary deck disposed above the lower deck and comprising a series of tall brackets interchangeable with the said low brackets, said tall brackets supporting a lower series of shuttle-guiding elements in alignment with those carried by the said low brackets to complete the said lower deck, and an upper series of shuttle-guiding elements disposed above the said lower series and constituting the said auxiliary deck, a reed comb between each adjacent pair of said brackets on said lower deck, a reed comb carried by each of said tall brackets on said auxiliary deck between a pair of vertically extending arms formed on each tall bracket, a base rib extending between said arms for supporting said comb vertically, and a pair of bars secured respectively on the front and back faces of the arms respectively and at the upper and lower ends of the comb for supporting said comb laterally.

10. In a narrow-ware loom, a lay having a lower shuttle deck comprising a series of low brackets respectively supporting a series of shuttle-guiding elements, an auxiliary deck disposed above the lower deck and comprising a series of tall brackets interchangeable with the said low brackets, said tall brackets supporting a lower series of shuttle-guiding elements in alignment with those carried by the said low brackets to complete the said lower deck, and an upper series of shuttle-guiding elements disposed above the said lower series and constituting the said auxiliary deck, a reed comb between each adjacent pair of said brackets on said lower deck, a reed comb carried by each of said tall brackets on said auxiliary deck, each of said tall brackets comprising a tongue adapted to be secured to said lay, a body portion adapted to extend above said lay and to which the shuttle guide elements of said lower deck are secured, arms extending above said body portion and spaced longitudinally of the lay for supporting the shuttle guide elements of said auxiliary deck and to provide a cavity for a reed 115

- 50 8. In a narrow-ware loom, a lay having a lower shuttle deck comprising a series of low brackets respectively supporting a series of shuttle-guiding elements, an auxiliary deck disposed above the lower deck and comprising a series of tall brackets interchangeable with the said low brackets, said tall brackets supporting a lower series of shuttle-guiding elements in alignment with those carried by the said low brackets to complete the said lower deck, and an upper series of shuttle-guiding elements disposed above the said lower series and constituting the said auxiliary deck, a reed comb between each adjacent pair of said brackets on said lower deck, and a reed comb carried by each of said tall brackets 120

- 55 60 65 and a reed comb carried by each of said tall brackets on said auxiliary deck, each of said tall brackets comprising a tongue adapted to be secured to said lay, a body portion adapted to extend above said lay and to which the shuttle guide elements of said lower deck are secured, arms extending above said body portion and spaced longitudinally of the lay for supporting the shuttle guide elements of said auxiliary deck and to provide a cavity for a reed 125

comb of the auxiliary deck, a base rib extending between the arms at the lower end of said cavity, a lower back rib extending between said arms above said base rib and 5 across said cavity, and an upper back rib extending across said cavity at the upper end thereof.

11. In a narrow-ware loom, a lay having a lower shuttle deck comprising a series of 10 low brackets respectively supporting a series of shuttle-guiding elements, an auxiliary deck disposed above the lower deck and comprising a series of tall brackets interchangeable with the said low brackets, said tall 15 brackets supporting a lower series of shuttle-guiding elements in alignment with those carried by the said low brackets to complete the said lower deck, and an upper series of 20 shuttle-guiding elements disposed above the said lower series and constituting the said auxiliary deck, a reed comb between each adjacent pair of said brackets on said lower deck, a reed comb carried by each of said tall brackets on said auxiliary deck, each of 25 said tall brackets comprising a tongue adapted to be secured to said lay, a body portion adapted to extend above said lay and to which the shuttle guide elements of said lower deck are secured, arms extending above 30 said body portion and spaced longitudinally of the lay for supporting the shuttle guide elements of said auxiliary deck and to provide a cavity for a reed comb of the auxiliary deck, a base rib extending between the 35 arms at the lower end of said cavity, a lower back rib extending between said arms above said base rib and across said cavity, an upper back rib extending across said cavity at the upper end thereof, and lugs extending longitudinally of the lay and outward from each 40 arm for supporting reed combs of the lower deck.

ANDREW WEIMAR.
